UNITED STATES PATENT OFFICE.

CHARLES W. TOOKE, OF WASHINGTON, DISTRICT OF COLUMBIA.

BOTTLE CLOSURE.

Application filed October 7, 1926, Serial No. 140,081. Renewed December 3, 1928.

This invention relates to bottle closures and has for an object to provide a closure for the type of bottle or jar ordinarily known as a milk bottle, embodying new and improved features of convenience and sanitation.

A further object of the invention is to provide a bottle closure embodying the features of the well known "pouring pull" but improved in that a liner is employed under the 10 scored disk.

A further object of the invention is to provide a disk with a liner associated therewith in position normally under the disk in operation upon a bottle, said disk being scored 15 from the under side, such scoring also completely severing the liner in registering with the scoring, so that the scored part of the disk may be lifted with the severed part of the liner therewith.

20 A further object of the invention is to provide a disk and liner secured together in any approved manner, one of which is a staple or the like passing through the liner and through the disk with a scoring of the disk 25 from the under side cutting the liner about the staple in such manner that manipulating the staple will cause a fracturing of the disk at the scored line, permitting the raising of the scored section with that section of the liner secured thereto by the staple.

With these and other objects in view, the invention comprises certain novel parts, elements, features, combinations and functions as disclosed in the drawing together with 35 mechanical and functional equivalents thereof as will be hereinafter more fully described and claimed.

In the drawings:

Figure 1 is a view of the invention by the 40 exhibition of a bottle partly in section and partly in elevation with the closure applied thereto shown substantially in diametrical section, the section passing also through the "pouring pull".

45 Figure 2 is an inverted plan view of the closure, a part of the liner being broken away to show the disk.

Figure 3 is a top plan view of the closure as it appears upon and in cooperation with 50 the bottle.

Figure 4 is a diametrical sectional view through the closure removed from the bottle but in cooperative shape with the pouring pull shown in open position as taken on line 55 4-4 of Figure 3.

Figure 5 is a diametrical sectional view

through the device before being applied to a bottle as taken on line 5-5 of Figure 2.

Like characters of reference indicate corresponding parts throughout the several 60 views.

The improved bottle closure which forms the subject matter of this invention is adapted to be applied to various bottles, jars and the like and the illustration at 10 of a conventional milk bottle is not intended as any limitation upon the invention or its utilities or functions. Whatever the shape of the bottle or its nominal utility, it will be provided 65 with a neck rabbet 11 forming a shoulder 70 upon which in the usual and ordinary use of the bottle a card board disk rests forming the closure.

The present invention embodies also a card board disk 12 secured to which is a liner 13 upon what is the normally under side of the disk as it is applied and as shown at Figure 1. This liner may be of any approved material such for instance as a thin paper impregnated with paraffine or other waxy material or a 80 resinous compound which will harden, and the invention is in no way limited to the precise nature of the liner.

The liner may be attached to the disk 12 over its entire surface by melting the wax or other impregnating material, if desired, but such attachment forms no part of the present invention. Under the present invention, the liner 13 is attached to the disk 12 by means of a staple 14 which may be the only attaching 90 means or may be merely supplemental. The staple 14 may and preferably will also attach a tab 15 for convenience of operation, but such tab is no limitation upon the invention.

About the staple 14 or its position, the disk 12 is scored, as shown at 16, from the normally under side stopping short of the upper surface, so that there remains uncut a thin portion of the disk on the upper or outer side, so that the disk in position upon the bottle will 100 exhibit an entirely unbroken, unscored, uncut surface. The scoring 16 of the disk 12 also forms a cut 17 through the liner 13. The staple 14, therefore, extends through a scored part of the disk 12 and through the completely 105 cut portion of the liner. In this way by using the tab 15 or any equivalent or substitute means, the scored section of the disk together with the severed section of the liner may be raised forming an opening through 110 the superposed disk and liner for the insertion of a straw, if desired, or serving as an opening

for pouring out the contents of the bottle. The severing of the upper or outer surface of the disk also forms a pouring pull which will close into closed position after a part of the 5 contents have been removed as distinguished from the scoring from the top which leaves a jagged edge about the pouring pull which prevents its being returned to normal seating. With the fractured edge outermost, however, 10 there is nothing to prevent the accurate return of the pouring pull to completely fill the opening and to thus close completely the bottle.

As shown in the drawings, the outer edges 15 of the liner 13 are crimped as at 18 over downwardly and about the neck of the bottle, creasing or scoring as at 19 being first provided in the manufactured article to provide for accurate and neat folding of the several crimps. Such folding or crimping is, however, not any 20 part of the present invention which includes merely the liner under the disk and is not in any way limited to the extent, formation or

disposition of the marginal portion of said liner.

What I claim to be new is:

1. A bottle closure comprising a disk of 25 relatively stiff sheet material, an independent liner of relatively flexible material under the disk and extending as an annulus therebeyond, scoring passing through the liner and into the 30 disk to form registering lips, and means passing through and securing the lips together to lift conjointly.

2. A bottle closure comprising a disk of 35 relatively stiff sheet material, an independent liner of relatively flexible material under the disk and extending as an annulus therebeyond, scoring passing through the liner and into the disk to form registering lips, a lifting tab and 40 means passing through and securing the tab and lips together to lift conjointly.

In testimony whereof I affix my signature.

CHARLES W. TOOKE
